(57) **CLAIM**

The ornamental design for a floor washing appliance as shown and described.

DESCRIPTION

The patent or application file contains at least one drawing executed in color. Copies of this patent or patent application publication with color drawing(s) will be provided by the Office upon request and payment of the necessary fee.

1. Floor washing appliance

2. Floor washing appliance

1.1 : Front

1.2 : Back

1.3 : Left

1.4 : Right

1.5 : Top

1.6 : Enlarged

1.7 : Bottom

1.8 : Enlarged

1.9 : Perspective

1.10 : Perspective

2.1 : Front

2.2 : Back

(Continued)

2.3 : Left**2.4** : Right**2.5** : Top**2.6** : Enlarged**2.7** : Bottom**2.8** : Enlarged**2.9** : Perspective**2.10** : Perspective

Reproductions **1.1** to **1.5** and **1.7** are six orthographic projection views of a first floor washing appliance which can be hand-held in use, and reproduction **1.6** is a top enlarged view thereof, reproduction **1.8** is a bottom enlarged view thereof and reproductions **1.9** and **1.10** are two perspective views thereof; reproductions **2.1** to **2.5** and **2.7** are six orthographic projection views of a second floor washing appliance which can be hand-held in use, and reproduction **2.6** is a top enlarged view thereof, reproduction **2.8** is a bottom enlarged view thereof and reproductions **2.9** and **2.10** are two perspective views thereof.

The portions of the design shown in the color yellow are for the purpose of illustrating portions of the floor washing appliance that form no part of the claimed design.

1 Claim, 16 Drawing Sheets
